UNITED STATES PATENT OFFICE.

JAMES W. SEE, OF HAMILTON, OHIO.

SIGNAL FOR STREET INTERSECTIONS.

1,268,288.

Specification of Letters Patent. Patented June 4, 1918.

Application filed July 3, 1914. Serial No. 349,660.

To all whom it may concern:

Be it known that I, JAMES W. SEE, a citizen of the United States, residing at Hamilton, Butler county, Ohio, have invented certain new and useful Improvements in Signals for Street Intersections, of which the following is a specification.

This invention pertains to signals for use at street intersections to aid the traffic- 10 officer, or, in cases, to act as a substitute for him. In guiding the traffic the device may give audible signals or readable signals or light signals, alone and together.

This invention will be readily understood 15 from the following description taken in connection with the accompanying drawings in which:—

Figure 1, is a front elevation of a signal exemplifying my invention:

20 Fig. 2, a vertical section of the same in the plane of line *a* of Figs. 3, 6, 11 and 12: Fig. 3, a horizontal section through the cabinet in the plane of line *b* of Figs. 1, 2, 5, 6, 7, 10 and 11:

25 Fig. 4, a diagram of the electric circuit: Fig. 5, a front elevation of the timing mechanism:

Fig. 6, a side elevation of the timing mechanism and horn-board:

30 Fig. 7, a vertical section, in the plane of line *c* of Fig. 5, of the timing mechanism:

Fig. 8, a vertical section of the timing mechanism in the plane of line *d* of Fig. 5:

Fig. 9, a vertical section of the timing 35 cylinder in the plane of line *e* of Fig. 5:

Fig. 10, a rear elevation of the horn-board:

Fig. 11, a vertical section of the horn-board in the plane of line *f* of Figs. 2, 10 and 12: and

40 Fig. 12, a plan of the horn-board, the sign shaft appearing in section in the plane of line *g* of Figs. 2, 6 and 11.

The device is intended to be fixedly disposed at the intersection of the center lines 45 of two streets, say, for example, Dearborn street and Jackson Boulevard, and to give such notice as will arrest the traffic on Jackson Boulevard while the traffic on Dearborn street moves for a given period, and to then 50 arrest the traffic on Dearborn street while the traffic on Jackson Boulevard moves, and so on and on.

In the drawings:—

1, indicates a column adapted to be fixedly planted in the intersection of the center lines 55 of two streets:

2, a doored cabinet carried by the column and adapted to contain mechanism pertaining to the signal and also adapted to contain, if desired, fire alarm, telephone and 60 police calls:

3, a vertical shaft, which I will call the sign-shaft, mounted for rotation in the column:

4, a sign secured to the upper end of the 65 shaft and adapted, by quarter turns of the shaft, to stand cross-wise of either street, the sign carrying a warning legend, the word "Stop" in the illustration:

5, a motor adapted to serve in turning the 70 sign-shaft:

6, ports in the cabinet to give freedom for the sound of the audible signal produced by apparatus within the cabinet:

7, an umbrella carried by the column above 75 the ports to protect the ports from the weather:

8, a disk secured to the shaft within the cabinet:

9, four equidistant stop-lugs carried by the 80 disk:

10, a stop-hook pivotally supported within the cabinet, its hooked end being adapted to engage any one of the stop lugs of the disk and hold the sign in position across 85 the center line of one of the streets:

11, a spring urging and holding the stop-hook to active position:

12, a solenoid:

13, a movable core of the solenoid:

14, a tappet mounted on the stop-hook:

15, a pin projecting from the stop-hook and adapted to be engaged by a tooth on tappet 14:

16, a spring coöperating with the stop-hook and tappet and holding the hook of the tappet yieldingly to pin 15:

17, a second tooth on the tappet, this tooth engaging a tooth carried by the core of the solenoid:

18, a spring holding the core of the solenoid outwardly against a suitable fixed stop:

19, a board fixed within the cabinet and supporting the solenoid and stop-hook and

other portions of the timing-mechanism and hereinafter termed the timing-board:

20, a clock-work mechanism carried by the timing-board:

5 21, an oscillating lever to serve in winding up the clock-work;

22, a timing-cylinder rotated at uniform rate by the clock-work, this cylinder being provided on its periphery with metallic surfaces connected with each other and with insulation between the metallic surfaces:

10 23, a complete circle of insulation at one end of the cylinder:

24, a circle of four equidistant metallic contact surfaces on the cylinder:

15 25, a circle of two equidistant metallic contact surfaces on the cylinder:

26, a single contact surface on the cylinder:

20 27, a circle of three equidistant metallic contact surfaces on the cylinder:

28, a circle of four contact surfaces on the cylinder, arranged in diametrically opposite pairs, each pair being twice as far from the other pair as one surface of the pair is from the fellow surface of that pair, all of the metallic peripheral contact surfaces of the cylinder being in electrical communication with each other:

30 29, a fixed dove-tailed guide-way parallel with the cylinder:

30, a carriage adapted for adjustment in the guide-way:

31, a brush carried by the carriage and adapted for contact with the metallic contact surfaces of the cylinder:

32, a latch mounted on the carriage and adapted to engage any selected one of a series of notches in the guide-way so as to 40 maintain brush 31 in the plane of rotation of any selected one of the circles of contact surfaces on the cylinder:

33, a metallic plate mounted on the timing-board and carrying much of the timing-45 mechanism:

34, one of the mains for bringing current to the apparatus, this main being illustrated as attached to plate 33:

35, the second main, this main being illustrated as leading to the solenoid and then through the motor:

36, a brush in constant contact with the peripheral metal of the cylinder and connecting main 35, through the solenoid and 55 motor, with the metallic peripheral surface of the cylinder: and

37, a normally open contact, illustrated as a push button, serving, when manipulated, to connect the two mains at a point beyond 60 the solenoid and motor.

Considering the parts as thus far referred to, let it be assumed that current is on the mains and that the clock-work is not wound up or that it is otherwise out of action, and

assume that the sign stands crosswise of one of the streets, say Jackson Boulevard, and assume that contact 31 rests on insulation, as indicated in Fig. 4.

The traffic officer may open the cabinet and, at his discretion manipulate button 37 thus putting current through the motor and through the solenoid. The core of the solenoid will, in an obvious manner, depress stop-hook 10 and permit the motor to turn the sign. When the tooth carried by the core has moved far enough to release the stop-hook from the lug on disk 8 the tooth of the core will disengage and pass tooth 17 of the tappet, whereupon spring 11 will restore the stop-hook to arresting position and the disk and sign will be stopped after having made a quarter turn, no matter how fast the motor may tend to turn the disk. The sign has thus been turned through an angle of ninety degrees or crosswise of Dearborn street and locked in such position by the stop-hook even if the officer failed to release the button. When he releases button 37, then the core goes out and its tooth takes the normal position as in Fig. 5, the swinging of tappet 14 permitting tappet-tooth 17 to be passed by the tooth carried by the core.

When, in the judgment of the officer, the proper time has arrived, he may manipulate button 37 again and turn the sign across Jackson Boulevard and so on and on. He may use his judgment as to the length of the period during which the traffic may be arrested on the respective streets, precisely as he would do by blowing his whistle in the usual manner.

In the above described use of the apparatus the officer's judgment and his manipulation of button 37 has been employed. Assume, now, that the traffic conditions were such that the officer's judgment need not be employed and that the traffic may be changed at regular intervals, and assume that a quarter minute is a satisfactory interval for alternately arresting the traffic on the two streets, and assume that the clock-work is in action and giving the cylinder one turn per minute. The officer will now shift brush 31 to the cylindrical circle 24 having four contacts fifteen seconds apart as the cylinder turns. The officer may now leave the station and thereafter the sign will automatically be given a quarter turn at each quarter minute, and the traffic may pass for a quarter minute on Jackson Boulevard while the traffic on Dearborn street is arrested for that length of time, and so on and on.

If, in the judgment of the officer, the traffic should be changed at one-half minute intervals instead of quarter minute intervals he sets brush 31 to the circle 25 carrying two contact surfaces on the cylinder. If he decides that the device should change the traffic

at the end of each minute he sets brush 31 to the circle 26 carrying one contact surface only. If he judges that the traffic should change at each one-third minute he sets 5 brush 31 to circle 27 which carries three contact surfaces on the cylinder. If it should prove that at all times or during certain hours the traffic is greater on one street than on the other he may provide that the 10 permission of traffic may remain upon one street twice as long as on the other. He may do this by setting brush 31 to circle 28 which has four contact surfaces so disposed that the traffic permission will be open for 15 periods of ten seconds on one street and twenty seconds on the other and, similarly the cylinder may be provided with other circles of contact surfaces so disposed relative to each other as to give any desired 20 difference in the permissive period for the streets.

Thus far the traffic over the intersecting streets has been effected by the showing of a sign under the direction of either the traffic 25 officer direct or automatically by the clock-work.

I will now describe the audible signal system to operate either alone or in conjunction with the sign system.

30 Proceeding with the drawings:—

38, indicates a board, which I will term the horn-board, supported in the cabinet:

39, an electrical operated audible signal device supported by the horn-board and 35 illustrated as an electric horn:

40, an insulated disk fast upon the sign shaft:

41, longitudinally extending metallic contact pieces mounted in the periphery of disk 40, there being six of these pieces, a pair diametrically opposite another pair and one contact piece in the middle of the space between each pair:

42, a pair of brushes making contact with disk 40 and adapted to be connected by contact pieces 41, one of these brushes being connected with electric main 35 through the horn, while the other brush is connected with main 34: and 43, a normally open push-button adapted to close the circuit through the horn from one main to the other.

Assume that the clock-work is out of operation and that brush 31 is on insulation on the cylinder, and that current is on the main.

55 The officer may, by manipulating push-button 43 sound the signal, say one blast of the horn for Jackson Boulevard and two blasts for Dearborn street, in other words he controls the movement of the traffic by 60 sound alone, on the same plan as he usually controls it by designating blasts upon his whistle.

If, now, he will shift brush 31 to circle 24 of four contact surfaces on the cylinder,

and will set the clock-work into motion, the sign will turn at quarter minute intervals as has been before described, the disk 40 turning and resting with the sign. If disk 40 turns, at the turning of the sign, one of the contact pieces 41 closes the circuit 70 through the horn and gives one blast. During the next quarter turn of the sign two blasts will be given and at the next quarter turn one blast and at the next quarter turn two blasts. The horn may thus indicate 75 which one of the two streets is being opened for traffic. It is desirable that the brushes 42 be so related to the contact pieces 41 that the horn is blown immediately upon the sign beginning its quarter turn. The horn 80 thus causes an audible signal in conjunction with the signal formed by the sign. If the clock-work be out of action and the signaling is to be done by the officer he may manipulate button 37 to bring about the quarter 85 turns of the sign as has been heretofore explained, and the turning of the sign-shaft brings about the appropriate blowing of the horn. In the diagram shown in Fig. 4 the brushes 42 are, for clearness of delineation, 95 shown separate but it is to be understood that these brushes are in the same vertical plane and both bearing on disk 40 so that the brushes are electrically connected with each other at each passage of a contact 95 piece 41.

Provision is also made for giving light signals to operate either alone or in conjunction with the sign-signal or horn-signal or both.

100

Proceeding with the drawings:—

44, indicates a pair of lights, one at or near each end of the sign, these lights being preferably electric lamps:

45, a shield carried by and disposed transversely to the sign between the two lamps:

46, a metallic disk mounted on but insulated from the sign-shaft:

47, a similar disk near the first one:

48, spots of insulating material breaking 110 the continuity of the peripheries of disks 46 and 47, there being four of these insulating spots disposed equidistantly on the peripheries of the disks: and

49, a pair of brushes, one bearing on the 115 periphery of each of disks 46 and 47, one of these brushes being connected with one of the mains, and the other brush with the other main.

The two lamps are in a circuit having 120 their terminals at disks 46 and 47 respectively, and the wiring between the lamps and the disks may be conveniently accomplished by making the sign-shaft hollow.

Quite regardless of the character of the 125 two signal-lights, when the signal is at the stopped position for one of the streets, two lights may be seen, one at each side of the

column, while from the intersecting street only one light is visible, shield 45, disposed between the two lights, serving to avoid confusion which might be due to parallax.

5 The two lights seen from the street on which traffic is for the instant closed will appear a certain distance apart, and the instant the device begins to turn to open that street to traffic the lights will appear to

10 approach each other until there appears to be but one light. At the same time the single light seen on the intersecting street will begin its movement due to the turning of the system, until two lights come into

15 view to bar the traffic on this street. It will thus be apprehended that there is a movement of the lights at the initiation of the turning of the system which is to release the traffic on one street and bar the

20 traffic on the other street. This premonitory movement of the lights at the initiation of the change of direction of travel is considered advantageous. And I prefer to enhance the advantage, in the case of electric lights, by a momentary extinction of

25 lights when the change of direction of traffic is to be made. This is accomplished in the illustrated example by the insulated spots 48 which cut out the lights for an instant

30 at each quarter turn of the shaft, and the insulated spots should be so related to brushes 49 that the circuit through the lights will be momentarily opened as quickly as practicable after the shaft starts

35 upon its quarter turn.

Continuing with the drawings:—

50, indicates the arbor of the clock-work which turns the timing-cylinder:

51, an arm fast on this shaft:

40 52, a stop projecting from carriage 30 and adapted when the carriage is shifted to the extreme left to come in the path of arm 51 and arrest the motion of the clock-work:

53, a manually operated switch for cutting the lights out of circuit: and

54, a manually operated switch for cutting the horn out of circuit.

It will of course be understood that, in the electric system particularly illustrated,

50 usual circuit-accessories, such as circuit-closers, lightning-arresters, resistances, etc., will be provided to such extent as will be needed, and it is also to be understood that

while convenience and compactness dictate

55 that the timing-mechanism and the push-buttons be disposed in a cabinet carried by the column, some or all of these parts may be elsewhere disposed so as to permit the control of the signal from a point distant

60 from the column.

I claim:

1. A signal device for use at the intersection of two streets comprising, a column, a shaft mounted for rotation on a vertical

axis on the column, a sign carried by the 65 shaft, a motor and a connection therefrom to the shaft for rotating the latter, devices for arresting and locking the sign in different angular positions, electrical means for controlling the rotation and locking of 70 the sign, and clockwork mechanism for controlling the electrical means, combined substantially as set forth.

2. A signal device for use at the intersection of two streets comprising, a column, 75 a shaft mounted for rotation on a vertical axis on the column, a sign carried by the shaft, a motor and a connection therefrom to the shaft for rotating the latter, devices for arresting and locking the sign in different angular positions, and clockwork mechanism for controlling the rotation and locking of 80 the sign, combined substantially as set forth.

3. A signal device for use at the intersection of two streets comprising, a column, 85 a shaft mounted for rotation on a vertical axis on the column, a sign carried by the shaft, a motor and a connection therefrom to the shaft for rotating the latter, devices 90 for arresting and locking the sign in different angular positions, electrical means for controlling the rotation and locking of the sign, a rotary cylinder bearing contact surfaces upon its periphery for controlling the 95 electrical means, and clockwork mechanism for turning said cylinder, combined substantially as set forth.

4. A signal device for use at the intersection of two streets comprising, a column, 100 a shaft mounted for rotation on a vertical axis on the column, a sign carried by the shaft, a motor and a connection therefrom to the shaft for rotating the latter, devices for arresting and locking the sign in different angular positions, electrical means for controlling the rotation and locking of the sign, a rotary cylinder provided on its periphery with several diverse series of contact surfaces, clockwork mechanism for 105 turning said cylinder, a brush coöperating with said cylinder and serving in conjunction with said contact surfaces to control the electrical means, and devices for adjusting said brush to any selected one of said 110 circles of contact surfaces, combined substantially as set forth.

5. A signal device for use at the intersection of two streets comprising, a column, an audible signal device supported thereby, 115 electrical means, comprising a motor, for controlling the sounding of said signal, and clock work mechanism for controlling said electrical means, combined substantially as set forth.

6. A signal device for use at the intersection of two streets comprising, a column, an audible signal device supported thereby,

- electrical means, comprising a motor, for controlling the sounding of said signal, a cylinder having contact surfaces upon its periphery to serve in controlling said electrical means, and clockwork mechanism for turning said cylinder, combined substantially as set forth. 5
7. A signal device for use at the intersection of two streets comprising, a column, a shaft mounted for rotation on a vertical axis on the column, a sign carried by the shaft, a motor, and a connection therefrom to the shaft for rotating the latter, devices for arresting and locking the sign in different angular positions, an audible signal device supported by the column, electrical means for controlling the rotation and locking of the sign, and means connecting the sign and audible signal device to cause the signal device to operate in harmony with the turning of the sign, combined substantially as set forth. 10
8. A signal device for use at the intersection of two streets comprising, a column, a shaft mounted for rotation on a vertical axis on the column, a sign carried by the shaft, a motor, and a connection therefrom to the shaft for rotating the latter, devices for arresting and locking the sign in different angular positions, an audible signal device supported by the column, electrical means for controlling the rotation and locking of the sign, means connecting the sign and audible signal device to cause the signal device to operate in harmony with the turning of the sign, and clockwork mechanism for operating the electrical means combined substantially as set forth. 15
9. A signal device for use at the intersection of two streets comprising, a column, a pair of lights supported by the column and arranged for rotation in a common horizontal plane, operative mechanism for turning and locking the pair of lights in different positions, a shield disposed in a vertical plane at right angles to the horizontal plane in which the lights rotate and between the two lights, and means for rotating the shield with the lights, combined substantially as set forth. 20
10. A signal device for use at the intersection of two streets comprising, a column, a pair of lights supported by the column and arranged for rotation in a common horizontal plane, operative mechanism for turning and locking the pair of lights in different positions, a shield disposed in a vertical plane at right angles to the horizontal plane in which the lights rotate and between the two lights, means for rotating the shield with the lights, and electrically controlled means for turning said shield and pair of lights in a horizontal plane, combined substantially as set forth. 25
11. A signal device for use at the intersection of two streets comprising a column, a shaft, mounted for rotation on a vertical axis on the column, a sign carried by the shaft, a motor and a connection therefrom to the shaft for rotating the latter, devices for arresting and locking the sign in different angular positions, signal lights supported by the sign near its ends, and electrical means for controlling the rotation and locking of the sign and pair of lights in angular positions, combined substantially as set forth. 30
12. A signal device for use at the intersection of two streets comprising a column, a shaft mounted for rotation on a vertical axis on the column, a sign carried by the shaft, a motor and a connection therefrom to the shaft for rotating the latter, devices for arresting and locking the sign in different angular positions, signal lights supported by the sign near its ends, electrical means for controlling the rotation and locking of the sign and pair of lights in angular positions, and means for momentarily extinguishing the lights when the sign begins its angular motion, combined substantially as set forth. 35
13. In signaling means for crossings and the like, the combination of a column, a sign rotatably mounted thereon, a positive lock for the sign, a motor connected to rotate the sign, means for releasing the lock and energizing the motor to rotate the sign, lights mounted to rotate with the sign, and means for blinking the lights during the rotation of the sign. 40
14. In signaling means for crossings and the like, the combination of a column, a sign rotatably mounted thereon, a positive lock for the sign, a motor connected to rotate the sign, means for releasing the lock and energizing the motor to rotate the sign, two lights carried by the sign and a shield between the lights to obscure the view of one of them at a time from certain positions. 45
15. In signaling means for crossings and the like, the combination of a standard, a rotatable sign thereon, a motor and locking means, a controlling circuit for the motor and locking means, and a timing controller for the circuit comprising moving contacts, a stationary contact, and means rendering the timing means inoperative by shifting one of the contacts. 50
16. In signaling means for crossings and the like, the combination of a standard, a rotatable sign thereon, a motor and locking means, a controlling circuit for the motor and locking means, and a timing controller for the circuit comprising annularly arranged moving contacts, a normally fixed contact, and means for shifting the last named contact to render the timing means ineffective. 55
17. In signaling means for crossings and

the like, the combination of a standard, a rotatable sign thereon, a motor and locking means, a controlling circuit for the motor and locking means, and a timing controller 5 for the circuit comprising annularly arranged moving contacts, a normally fixed contact, means for shifting the last named contact to render the timing means ineffective, and a stop carried by said last named contact to arrest movement of the timing means.

18. In signaling means for crossings and the like, the combination of a standard, a

rotatable sign, a motor and locking means therefor, an electrical controlling circuit 15 comprising a timing cylinder having a plurality of sets of contacts, a normally stationary contact to coöperate with the contacts of the cylinder; means for shifting the normally fixed contact and clockwork mechanism for rotating the cylinder.
